UNITED STATES PATENT OFFICE.

HENRY A. RIEMANN, OF HANNIBAL, MISSOURI.

CONCRETE-PILE-MAKING MACHINE.

1,030,267.

Specification of Letters Patent.

Patented June 18, 1912.

Application filed December 22, 1909. Serial No. 534,454.

To all whom it may concern:

Be it known that I, HENRY A. RIEMANN, a citizen of the United States, residing at Hannibal, in the county of Marion and State 5 of Missouri, have invented certain new and useful Improvements in Concrete-Pile-Making Machines, of which the following is a specification.

This invention has relation to certain new 10 and useful improvements in concrete pile making machines.

My invention has for its primary object the provision of an improved machine which will operate in an efficient manner to roll a 15 wire fabric covered with a concrete layer, and reinforced by a plurality of primary securing wires and a plurality of lengthwise positioned metal reinforcing rods.

A further object is to provide a machine 20 including the combination of certain mechanical instrumentalities by means of which cylindrical, or tapered pointed piles may be made in an efficient manner having finished outer surfaces and reinforced by 25 means of a plurality of primary supporting wires and embedded convolutely formed wire fabric reinforced by means of suitable lengthwise positioned strengthening rods.

With the above and other objects in view 30 the present invention consists in the combination and arrangement of parts as will be hereinafter more fully described and particularly pointed out in the appended claims, it being understood that changes in the specific structure shown and described may be 35 made within the scope of the claims without departing from the spirit of the invention.

In the drawings forming a part of this 40 specification, and in which like numerals of reference indicate similar parts in the several views, Figure 1 shows a side elevational view of a machine embodying my invention. Fig. 2 shows an end view thereof with a 45 fragmentary portion of the car. Fig. 3 shows an end view of the car with its fragmentary portion of the winding shaft. Fig. 4 shows a top view.

Referring to the drawings, the frame of 50 the machine comprises the longitudinal base sills 1, extending between the ends of which are transversely arranged sills 2. Extending vertically from each end of each of the sills 1 is an upright member 3 and at a suitable distance from these uprights, within 55 the frame, are the uprights 4. Arranged

parallel to the sills 2, and disposed across the upper ends of the uprights 3 and 4 are the spacing bars 5, which support at their opposite ends the longitudinally arranged stringers 6. Arranged in parallel relation above 60 the uppermost of the sills 2, and secured to the uprights 3 and 4, respectively, are the similar spacing bars 7 and 7', on which are mounted, on their opposite ends, the adjusting jacks 8 and 8'. These jacks have the 65 screw bars 9 and 9' which support the adjustable transverse bars 10 and 10', said bars being vertically adjustable by means of the bolts 22 arranged in the bars and passing through the vertically arranged elongated 70 slots 23 in the said uprights. Mounted on the upper face of the bars 10 and 10' are the journal bearing boxes 11, 11', and 13', while extending from the lower face of these bars are the similar boxes 12 and 12'. Ex- 75 tending through the boxes 11 and 11', and at either end of the frame between the uprights 3 and 4 is a shaft 20, having thereon a gear 19, meshing with a smaller gear 18 on a shaft 17 mounted in the boxes 13 and 13'. 80 On this shaft 17 is a larger gear 16 meshing with a gear 15 on a shaft 14 which is mounted in the boxes 12 and 12'. Carried by the shaft 20 is a drum 47, and on the shaft 17 is a similar drum 53, the purpose of which 85 will be later referred to.

Secured between each set of the bars 35 and 36 are the vertically arranged guides 27 between which are mounted to slide vertically a journal box 30. This box is divided 90 into two parts, so as to permit the insertion of the pivoted journal bearing 33, which is adapted to swing on the trunnions 32 engaged in suitable recesses in the box 30. The box is provided with the guide flanges 95 31, which engage the vertical members 27. Formed on the upper side of the box 30 is the eye member 34, to which is attached one end of a rope or other suitable cable 49, which passes over the pulley 50 mounted in 100 the bearings 51 on the cross bar 5, the opposite end of the rope being wound on the drum 47. Thus when the drum 47 is rotated in one direction the rope 49 will be wound thereon to draw the box 30 upwardly. 105 Mounted in the openings 63 of the journal bearings 33 is the forming roll 64, which is adapted to bear against the face of the pile to shape the same. Mounted in the box 25, on the bars 36, are the angle arms 62, hav- 110

ing mounted in the ends of the portions 57, a finishing roll 58, and secured at the angle of the arm, as at 56, is one end of a cable 54, which passes upwardly over the pulley 55, 5 mounted on the under face of the bar 5, and has its other end wound on the drum 53. It will thus be seen that upon rotation of the shaft 20, in the forming of the pile, the drum 47 will wind the cable 39 and raise the 10 roll 64 as the size of the pile increases, and at the same time the drum 53 will wind the cable 54 and raise the arm 62. To permit the arm 62 and the box 30 to fall down to normal position, I provide each of the drums 15 47 and 53 with a clutch, adapted to be released by means of the lever 48, the weight of said arm and box being sufficient, when the clutches of the drums are released, to permit them to drop and unwind the cables 20 from the drums.

The stringers 6 are properly braced by means of the truss form which comprises the depending bars 59 and the truss member 60.

25 Below the roll 64 and mounted in the couplings 70 by means of the fastening member 71 is the pile winding shaft or arbor 73, having formed thereon the wire retaining hooks 74. Thus when the bars 10 and 10' 30 are raised by means of the jacks 8 and 8', the shaft 73 will be raised also, thus permitting either end of the shaft to be raised, or lowered independently of the other end, the purpose of which will appear in the 35 description and operation of the machine.

Arranged across the sills 1 are the three tracks 75 for engagement between the wheels 76 which support the carriage 70. This carriage comprises the longitudinal beams 40 72 and the transverse beams 71' which support the table 70'. Extending transversely of the carriage and through one end of each of the longitudinal bars 72 is a rear shaft 73' on which is mounted a series of reels 75' 45 having the wire "A" wound thereon. Mounted transversely at the opposite end of the carriage are the parallel pile supporting rolls 80 and 81 mounted in the bearing blocks 83 on the bar 72. At the end of the 50 carriage adjacent to the rolls 80 and 81 is a wire roller 76' over which passes the wires from the drums 75', across the table 70' and have their free ends attached to the hooks 74 on the shaft 73. At the end of the rollers 55 80 and 81 is a truncated cone shaped roller 65 mounted in the bearing blocks 83'.

The reels 75' are mounted to turn with the shaft 73, and when sufficient wire has been 60 unwound and disposed across the table 70' it is necessary to stop the shaft so that the wires when wound on the shaft 73 will draw the carriage forward. To do this I provide a brake device of any suitable form, to hold the shaft 73' stationary in its bearing, the 65 form shown in the drawing being the pin 84

adapted to be passed down through an opening 85 in the end of the shaft, the end of the pin engaging against a stop pin 86 in one of the bars 72.

The operation of the machine, for making 70 cylindrical piles, is as follows: The wires A are unwound from the spools 75', drawn under the carriage, over the rollers 76', 80, and 81, across the platform 70', to the shaft 73 where their respective ends are secured 75 each to a hook 74. Woven or expanded metal sheets are then laid on top of the wires A and the platform 70'. Concrete is then shoveled thereon and smoothed in an even layer. The rollers 64 and 80 and 81 80 together with the shafts 73 are adjusted in parallel relation by means of the jacks 8 and 8'. The machine is then set in operation which, through means of the gears 15, 16, and 19 cause the rotation of the shaft 73, 85 and the wires, fabric, and concrete to be rolled thereon. As the shaft 73 rotates, and winds the material thereon, the wires A draw the carriage until the rollers 80 and 81 are beneath the shaft 73, when the wires 90 A may be cut. The material for the pile is now located between the rollers 64 and the rollers 80 and 81, and also the tapered rollers 65 and 65'. The continued rotation of the parts of the machine shape the pile into 95 cylindrical form, with the exception of the end between the tapered rollers which is given a corresponding taper. At the same time that the materials are being wound on the shaft 73, the drum 47 and 53 wind up the 100 cords 49 and 49' 54 and 54' and draw the rollers 58 and 64 up as the diameter of the pile increases. The former roll 58 rests against the face of the pile and serves to finish the same, smoothing the surface, and 105 scraping off superfluous concrete. This finishing operation is continued until the concrete has set enough to be easily handled, when the shaft 73 may be taken from its bearings, and withdrawn from the pile, the 110 pile being set away to harden. The machine is then reversed, and the carriage moved back to the original position.

To form a cylindrical pile without the tapered end, the operation is the same, except that the rollers 65 and 65' are removed.

When it is desired to make a pile tapered in its entire length, one end of the shaft 73 is raised by means of one or the other of the sets of jacks. The roller 64 is also similarly adjusted, but at its opposite end, so that the longitudinal space between the roller 64 is tapered. By means of the pin and slot connections 22 and 23 the beams 10 120 may be adjusted to incline the shaft 73 laterally. The movements of the parts are the same as above described with reference to the cylindrical pile, the outer face of the pile longitudinally thereof being inclined instead of horizontal. The sliding bear- 130

ings 30 are adapted to be adjusted so that the roller 58 will be arranged to scrape the tapered face of the pile at all points thereof.

Having thus described my said invention, 5 what is claimed is:

1. A pile making machine having in combination, a supporting standard, a core shaft, a horizontally traveling platform, a pivotally held finishing roller, a vertically reciprocating former roller, means for rotating said core shaft and synchronously moving said platform in a horizontal plane, 10 said finishing roller in an arc and the former roller in a vertical plane.
2. The combination with a suitable supporting frame, of an adjustably held driving shaft, a stub shaft, means to connect said driving shaft with said stub shaft, a core shaft, means to connect said core shaft to 15 said stub shaft, a slidably held former roller, oppositely positioned swinging cranks, a finishing roller carried by said cranks, a platform movably held below said core shaft, and means for synchronously moving 20 said former roller, finishing roller and platform from their normal position.
3. In combination, a supporting standard, a driving shaft, a drum shaft, means to connect said shaft, a stub shaft, means to connect said stub shaft to said drum shaft, a core shaft detachably secured to said stub shaft, a traveling platform held below said core shaft, vertically sliding bearings, 25 means to connect said bearings to said drum shaft, a former roller carried by said bearings, two pivotally held arms, a finishing roller carried by said arms, means to connect said arms to said drum shaft, a platform, pliable members extending from said 30 platform and secured to said core shaft.
4. The combination with a supporting

standard, of a driving shaft, a drum shaft, gears connecting said shafts, a stub shaft, a gear carried by said stub shaft to mesh with a gear carried by said drum shaft, a core 45 shaft detachably secured to said stub shaft, means to raise and lower said core shaft, a traveling platform, rollers carried by said platform, pliable connections extending from said core shaft to said platform, vertically sliding bearings, a former roller carried by said sliding bearings, two pivotally held arms, a finishing roller carried by said arms, a hoisting line extending from said sliding bearings to said drum shaft, and a 50 hoisting line extending from said pivotally held arms to said drum shaft.

5. The combination with a suitable supporting frame, of a driving shaft, a drum shaft, means to connect said shaft, a stub 60 shaft, means to connect said stub shaft to said drum shaft, a core shaft, means to detachably connect said core shaft to said stub shaft, vertically sliding bearings held proximal to said core shaft, an idler roller carried 65 by said sliding bearings, hoisting lines extending from said sliding bearings to said drum shaft, two pivotally held arms, an idler roller carried by said arms, hoisting lines extending from said idler roller to said 70 drum shaft, a horizontally movable platform, two adjustably held idler rollers carried by said platform, and pliable connections extending from said core shaft and secured to said platform. 75

In testimony whereof I affix my signature, in presence of two witnesses.

HENRY A. RIEMANN.
